UNITED STATES PATENT OFFICE.

CRAIG H. RICHEY, OF BIRMINGHAM, MICHIGAN.

DESIGN FOR A FRATERNITY PIN.

Application filed May 5, 1924. Serial No. 9,487. Term of patent $3\frac{1}{2}$ years.

To all whom it may concern:

Be it known that I, CRAIG H. RICHEY, a citizen of the United States, residing at Maple and Franklin Roads, Birmingham, in the county of Oakland and State of Michigan, have invented a new, original, and ornamental Design for a Fraternity Pin, of which the following is a specification, ref-

erence being had to the accompanying drawing, forming a part thereof.

Fig. 1 is a plan view of a pin showing my new design. Fig. 2 is an end view.

I claim:

The ornamental design for a fraternity pin, as shown.

CRAIG H. RICHEY.
